ATTORNEY.

UNITED STATES PATENT OFFICE.

JULIET LA CROIX, OF LOS ANGELES, CALIFORNIA.

DESIGN FOR A PINCUSHION.

54,934.

Specification for Design.

Patented Apr. 20, 1920.

Application filed June 24, 1919. Serial No. 306,480. Term of patent 3½ years.

To all whom it may concern:

Be it known that I, JULIET LA CROIX, a citizen of the United States, residing at Los Angeles, in the county of Los Angeles and State of California, have invented a new, original, and ornamental Design for Pin-cushions, of which the following is a specification, reference being had to the accompanying drawing, forming a part thereof.

Fig. 2 is a side elevation of a pin cushion showing my new design.

I claim:

The ornamental design for a pin cushion as shown.

JULIET LA CROIX.
